(57) **CLAIM**

The ornamental design for a plumbing fixture, as shown and described.

DESCRIPTION

In a preferred embodiment, the nature of this product is as a plumbing fixture in the form of a water closet and a base for a water closet.

FIG. 1 is a right, top, front perspective view of a plumbing fixture embodying my new design;

FIG. 2 is a top plan view thereof;

FIG. 3 is a front elevational view thereof;

FIG. 4 is a right side elevational view thereof, the left side elevational view thereof being a mirror image of the right side shown;

FIG. 5 is a rear elevational view thereof; and,

FIG. 6 is a bottom plan view thereof.

The broken line representations of a bowl opening internal structure and holes in FIGS. 1 and 2, rear structure in FIG. 5, and underside structure in FIG. 6, are for the purpose of illustration only, and form no part of the claimed design.
